(57) **CLAIM**

The ornamental design for a portable foldable mobile phone stand, as shown and described.

DESCRIPTION

FIG. 1 is a perspective view of the portable foldable mobile phone stand showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1; and,

FIG. 11 is a partial enlarged view of portion 11 in FIG. 2. The broken lines shown in the drawings represent portions of the portable foldable mobile phone stand that form no part of the claimed design. The dot-dash lines are included for the purpose of showing the enlarged areas.
